(57) CLAIM

I claim the ornamental design for the athletic glove holder, as shown and described.

DESCRIPTION

The present application claims the benefit of U.S. Design patent application Ser. No. 29/239,888, filed Oct. 5, 2005. FIG. 1 is a front view of the athletic glove holder.

FIG. 2 is a rear view of the athletic glove holder.

FIG. 3 is a side view of the athletic glove holder; and,

FIG. 4 is an opposite side view of the athletic glove holder.
